UNITED STATES PATENT OFFICE.

GEORGE W. PURCELL, OF BLACK HAWK, MISSISSIPPI.

COTTON-HARVESTER.

SPECIFICATION forming part of Letters Patent No. 310,314, dated January 6, 1885.

Application filed November 21, 1883. (No model.)

To all whom it may concern:

Be it known that I, GEORGE W. PURCELL, of Black Hawk, in the county of Carroll and State of Mississippi, have invented a new and Improved Cotton-Harvester, of which the following is a full, clear, and exact description.

The object of my invention is to provide a new and improved machine for picking cotton, which machine can be held to the body and operated by hand.

The invention consists in the construction and arrangements of parts, as will be herein-after described and claimed.

Reference is to be had to the accompanying drawings, forming part of this specification, in which similar letters of reference indicate corresponding parts in all the figures.

Figure 1 is a longitudinal elevation of my improved cotton-picker, parts being shown in section. Fig. 2 is a sectional plan view of the same. Fig. 3 is a sectional elevation of the same on the line $x x$, Fig. 1.

A shaft, A, is journaled in the ends of the prongs of a fork, B, formed on the end of a rod, C, provided with a plate, C', and a belt, C", for holding and securing it to the body. On the shaft A a disk, D, is rigidly mounted, the thickness of which disk decreases slightly from the middle toward the edge, which is rounded off. The surface and edges of the disk are covered with coarse carding-cloth or with picker-teeth a . On each hub D' of the disk D a bevel cog-wheel, E, is formed, which cog-wheels engage with bevel-pinions F, mounted on the ends of shafts G, held about parallel with the disk D on the shanks of the fork, on which shaft G clearer-brushes H are rigidly mounted. On one end of the shaft A a pinion, J, is mounted which

engages with a cog-wheel, K, pivoted to one 40 of the shanks of the fork, and provided with a handle, L, for revolving it. If the picker has a double wedge-shaped cross-section, as shown, a greater surface of the said disk can be presented to the cotton.

The operation is as follows: By means of the wheel K the picker-disk D is revolved in the direction of the arrows a' —that is, toward the operator. The picker-teeth catch the cotton and tear it from the plants. The clearer-brushes H are revolved much more rapidly than the disk D, and brush the cotton from the teeth a . From the brushes H the cotton drops into a suitable receptacle held below the picker.

Having thus described my invention, I claim as new and desire to secure by Letters Patent—

1. In a cotton-harvester, the combination of the fork B and the disk D, journaled in the outer ends thereof, with the clearer-brushes H, journaled within the fork at opposite sides of the disk D, pinion J on the outer end of the shaft of the disk D, and pinion K, meshing therewith for revolving the disk, substantially as set forth.

2. In a cotton-harvester, the combination, with the picker-disk D, mounted on the shaft A, journaled in the fork B, of the bevel cog-wheels E, formed on the hub of the disk, the bevel-pinions F, the clearer-brushes H, the pinion J on the shaft A, and the cog-wheel K, engaging with the pinion J, substantially as herein shown and described.

GEO. W. PURCELL.
